CLAIM

The ornamental design for a cartridge, as shown and described.

DESCRIPTION

FIG. 1 is a front view of a first embodiment of a cartridge;
FIG. 2 is a rear view thereof;
FIG. 3 is a top plan view thereof;
FIG. 4 is a bottom plan view thereof;
FIG. 5 is a left side view thereof;
FIG. 6 is a right side view thereof;
FIG. 7 is a front, top perspective view thereof;
FIG. 8 is a rear, bottom perspective view thereof;
FIG. 9 is a front view of a second embodiment of a cartridge;
FIG. 10 is a rear view thereof;
FIG. 11 is a top plan view thereof;
FIG. 12 is a bottom plan view thereof;
FIG. 13 is a left side view thereof;
FIG. 14 is a right side view thereof;
FIG. 15 is a front, top perspective view thereof; and,
FIG. 16 is a rear, bottom perspective view thereof.
The broken lines shown in the drawings illustrate portions of the cartridge that form no part of the claimed design.
